UNITED STATES PATENT OFFICE.

HARDY L. CATHEY, OF ERICK, OKLAHOMA.

COTTON-SEED HULLER.

No. 889,869.

Specification of Letters Patent.

Patented June 2, 1908.

Application filed July 25, 1907. Serial No. 385,546.

To all whom it may concern:

Be it known that I, HARDY L. CATHEY, citizen of the United States, residing at Erick, in the county of Greer, Oklahoma, have invented certain new and useful Improvements in Cotton-Seed Hullers, of which the following is a specification.

This invention has for its object a simple durable and efficient construction of cotton 10 hulling machine, designed to prepare the seed cotton to enter the gin free from burs, dirt, sticks and other foreign substance, thereby greatly prolonging the life of the gin proper and producing other advantageous 15 results hereinafter specifically set forth.

For a full understanding of the invention and the merits thereof and also to acquire a 20 knowledge of the details of construction and the means for effecting the result, reference is to be had to the following description and accompanying drawings, in which:

Figure 1 is a side elevation of my improved cotton hulling machine. Fig. 2 is a top plan view thereof. Fig. 3 is a longitudinal 25 sectional view. Fig. 4 is a detail perspective view of the feed plate.

Corresponding and like parts are referred to in the following description and indicated in all the views of the drawings by the same 30 reference characters.

Referring to the drawings, the numeral 1 designates the casing of my improved cotton hulling machine, said casing being separated from the breast 2 by means of the inclined 35 slotted board 3 producing a series of ribs 3^a. Saws 4 are mounted on the shaft 5 in the framework 6 so as to project through the spaces between the several ribs 3^a into the breast.

40 A feed bed 7 is mounted on a rod 8 in slotted bearings 9 in the breast, so that the said feed bed may be tilted to different inclinations or raised up and down to suit the requirements of feeding.

45 10 designates an apron which is provided with a series of transverse slats 11 and which is mounted on the transversely extending rollers 12 and 13 journaled in bearings 14 at the top of the breast. The apron 10 is inclined, as shown, and extends into close proximity with the inclined board 3 at the upper ends of the ribs 3^a, with its lower stretch running in a straight line from the ribs for a purpose hereinafter described in 50 connection with the description of the operation of the machine. The roller 13 of the

endless apron 10 carries a pulley 15 which is connected by means of a belt 16 with a similar pulley 17 mounted on the shaft 5 of the saws 4 so as to operate the apron. 60

Within the casing 1 is a toothed cleaning drum 18 designed to disengage the seed cotton from the ribs as it is drawn therethrough by the series of saws 4. 19 designates a suction flue underneath the casing and designed 65 to receive the seed cotton and carry it out to the gin proper, through suitable feeding means (not shown).

The drive shaft 20 of the machine is provided with a belt wheel 21 which extends 70 around an idler 22 and thence over a pulley 23 on the shaft 24 of the shaft cleaning drum 18. Said belt also extends around the pulley 25 on the end of the shaft 5 so as to revolve the saws. 75

In the practical operation the machine receives the cotton, burs, seed and lint together and separates the seed and lint from the hulls or burs, the latter going out in front of the machine, and the seed and lint being caught 80 by the saws and carried to the ribs and thence disengaged from the ribs and dropped in the suction flue and thence carried to the gin proper. The cotton, in the hulls or burs, just as it comes from the stalks, is fed over 85 the breast against the adjustable feed bed 7, and moves upon the same into contact with the saws, the teeth of which are so formed as to readily take hold of the cotton and free it from the hulls, but in such a manner as to not 90 cut or break the fibers or release the lint from the seed. As soon as the cotton comes in contact with the saws, it is carried to the inclined ribs 3^a where it meets the reverse motion of the endless apron 10, which is revolved 95 very rapidly and so agitates the cotton as to form a complete but fluffy roll without the necessity of forcing a roll by heavy feeding which would increase the density of the roll, this being a very advantageous feature of my 100 machine. Furthermore, it will be noted that the apron 10, by its motion prevents the machine from packing or choking and this is the main separating element of the machine, as all burs, stalks, and other foreign matter, are 105 thrown back over the cotton in the roll and fall out in front, as the front of the breast 2 is entirely open and unobstructed between the apron and feed bed thereby leaving the seed cotton fluffy and in proper condition to enter 110 the gin proper. The apron 10 keeps the cotton in motion in the breast of the huller until

practically all of the seed cotton has been separated from the burs and dirt. The said burs and the like, when they fall out in front of the machine, preferably enter a suction flue (not shown) that delivers them into the engine room so that they may be utilized as fuel, and thereby effect a saving.

From the foregoing description in connection with the accompanying drawing, it will be seen that I have provided a cotton hulling machine which is simple in construction and not liable to get out of order and which is an efficient agitator and separator of the burs and dirt, stalks and the like from the seed cotton, preparatory to feeding the seed cotton into the gin.

Having thus described the invention, what is claimed as new is:

1. A cotton hulling machine, comprising a casing, a breast, a series of ribs separating the casing from the breast, a feed bed mounted in the breast, a series of saws mounted in the casing and projecting through the spaces between the ribs into the breast, an inclined endless apron mounted in the breast with its lower stretch running in a straight line away from the ribs, means for imparting a traveling movement to the apron, and means for driving the saws, the entrance opening or front of the breast being unobstructed between the apron and feed bed.

2. A cotton hulling machine, comprising a casing, a breast, a series of ribs separating the casing from the breast, a feed bed mounted in the breast, a series of saws mounted in the casing projecting through the spaces between the ribs into the breast, means for driving said saws, an inclined endless apron mounted in the breast with one roller located in close proximity to the saws and ribs, and with its lower stretch running in a straight line away from the said ribs and saws, said apron embodying a series of transverse slits, and

means for imparting movement to the apron, the entrance opening or front of the breast 45 being unobstructed between the apron and feed bed.

3. A cotton hulling machine, comprising a casing, a breast, a series of ribs separating the casing from the breast, a series of saws mounted in the casing and projecting through the spaces between the ribs into the breast, means for driving the saws, an inclined endless apron mounted in the breast with its lower stretch running in a straight line away 55 from the ribs, means for imparting a traveling movement to the apron, and a feed bed mounted in the breast and forming with the lower stretch of the apron an entrance opening for the front of the breast which is entirely unobstructed from the saws outwardly between the bed and apron, the apron being outwardly diverging with respect to the bed as a whole.

4. A cotton hulling machine, comprising a casing, a breast, a series of ribs separating the casing from the breast, a series of saws mounted in the casing and projecting through the spaces between the ribs into the breast, means for driving the saws, a feed bed mounted in the breast, an inclined endless apron mounted in the breast above the feed bed and embodying a series of transverse slats, the lower stretch of the apron running in a straight line away from the ribs and the 75 apron diverging outwardly from the bed as a whole, the space between the bed and apron being entirely unobstructed or unrestricted, and means for imparting a traveling movement to the apron.

In testimony whereof I affix my signature in presence of two witnesses.

HARDY L. CATHEY. [L. S.]
